UNITED STATES PATENT OFFICE

105,677

DESIGN FOR A DRESS

Philip Wenett, New York, N. Y.

Application July 15, 1937, Serial No. 70,459

Term of patent 3½ years

To all whom it may concern:

Be it known that I, Philip Wenett, a citizen of the United States of America, residing in Manhattan, county of New York, and State of New York, have invented a new, original, and ornamental Design for a Dress, of which the following is a specification, reference being had to the accompanying drawing, forming part thereof, wherein,

The design is characterized by the specific arrangement of the ribbon trimming, superimposed on the dress, as shown.

I claim:

The ornamental design for a dress, substantially as shown, and described.

PHILIP WENETT.
